UNITED STATES PATENT OFFICE.

WILLIAM S. DUNHAM, OF SHARPSVILLE, PENNSYLVANIA.

CONCRETE FORM.

Application filed March 31, 1921. Serial No. 457,400.

To all whom it may concern:

Be it known that I, WILLIAM S. DUNHAM, a citizen of the United States, and a resident of Sharpsville, in the county of Mercer 5 and State of Pennsylvania, have invented a new and useful Improvement in Concrete Forms, of which the following is a specification.

This invention relates to concrete forms. 10 More particularly it relates to such structures adapted to form a comparatively thin wall of concrete, and to means for continuously, or intermittently, raising such forms, in order that fluid concrete may be continuously 15 poured onto the top of the wall being formed. The object is to provide a form and lifting apparatus which will permit the continuous building up of a concrete wall, without the necessity of tearing down, rebuilding or extending the form molding the walls. Another object is to provide means 20 for passing girders, sashes, etc., without breaking the form.

The many uses and advantages of the invention 25 will appear more fully in the following specification.

Referring to the drawings Fig. 1 is a diagrammatic plan view of my form applied to a wall such as of a small dwelling house, 30 or the foundation thereof; Fig. 2 is a vertical partial section on the line II—II, Fig. 1, showing details of the hoisting apparatus; Fig. 3 is an enlarged partial plan view of a portion of the form; Fig. 4 is an enlarged 35 side elevation of a portion of the form; Fig. 5 is a vertical section on the line V—V of Fig. 4; and Fig. 6 is an enlarged partial plan view showing details of the hoisting apparatus and connection of the shafts used 40 therewith.

In building concrete walls it is necessary to set up a form to mold the concrete while it sets. This ordinarily consists of two plain smooth walls set at a distance apart equal 45 to the thickness of the wall that is to be built. The usual way of doing this is to build these walls of wood, supporting them by exterior braces and possibly by connecting wires, then to fill in the space between 50 these two wooden members with liquid concrete. After the form has been filled it is allowed to stand for a certain time until the cement has set, when the forms are torn down and rebuilt above that portion of the 55 wall which has been so formed. This operation is continued by successive steps until

the wall has been built to the required height. The tearing down and building up operations are expensive, resulting in gradual destruction of the lumber that is used, 60 and in addition the walls are some times defective on account of the new concrete not making an adequate bond with that which has previously been laid. Metal forms have been used, but, so far as I know, have always 65 been put into position, filled with concrete which is allowed to set, then removed, raised to a new height, refilled, etc.

The present invention provides an all-metal construction which may be retained 70 in place by the wall which is being built, no exterior braces being necessary, and provides means for continuously, or intermittently, lifting such forms as fast as the new concrete is poured in and sets, so that the building 75 operation may be carried on continuously. That is to say, without any loss of time due to removal or raising of the forms.

In Fig. 1, which illustrates diagrammatically a form adapted to mold the entire 80 outer wall of a building, a motor 1 is illustrated. This drives a shaft 2, which is connected through a series of gears, not illustrated, to a chain 3, which drives a sprocket 4, keyed on the end of a shaft 5. This shaft 85 5 extends along one entire side of the building, and is positioned substantially over the middle portion of the wall that is to be built. The shaft is supported at appropriate points 90 by bearings 6, carried on extensions 7 from supporting pillars 8, which are seated upon the earth, or some other fixed support, independent of the molding form itself. A number of universal joints 9 are provided in the shaft 5, which also carries at its end near 95 the sprocket 4, a beveled gear 10, which meshes with a similar gear 11, keyed on the end of a shaft 12, which is similar to the shaft 5 first referred to. At the other end of the shaft 12 there is a similar gear 100 13, meshing with a gear 14, on the end of a similar shaft 15, which extends along the entire side of the frame. This shaft 15 carries at its other end a similar beveled gear 16 meshing with a gear 17 on the end of a 105 similar shaft 18, extending along the adjacent wall.

The shaft 5 carries at the end opposite the point where it is driven a beveled gear 19, meshing with a similar gear 20, on shaft 21, which extends along the side of the frame. The shaft 21 is similarly connected through

beveled gears 22 and 23 to a similar shaft 24 extending along the last side of the form. A sufficient number of the supports 8 are provided to carry the trains of shafting above described and to support them. At the corners, these supports 8 have lateral braces 30, and the intermediate supports 8 have similar rearwardly extending braces 31, as illustrated. These braces extend to the ground surface or to any other stable support.

By this arrangement when the motor 1 is driven all of the shafts will be rotated. At suitable intervals on each of the shafts 15 there are fixed sprocket wheels 40 which carry chains 41, as more clearly illustrated in Fig. 2.

The form itself for retaining the concrete is made up of a series of steel plates 50. 20 At each end of each of these plates an angle iron 51 is riveted, and the adjacent plates are joined together by means of bolts 52 extending through the sides of these angles, as clearly illustrated in Figs. 3 and 4. Intermediate the ends of the plates 50, and on the external sides thereof are riveted other angle irons 53. These have three or 25 more holes 54 in the portions that extend above the upper edge of the plates 50. These extensions may be of any desired 30 length, according to the particular construction that is being carried on. It is material, however, that the holes 54 be situated at a material distance apart since the outer wall made up of plates 50, and the 35 inner wall made up of plates 50^a are spaced apart and retained in fixed relative position by means of two braces 56 and 57, which extend between a pair of the projecting angles 53, situated on the exterior side 40 of two of the plates which are in position to form the side of a section of the concrete wall. This is clearly illustrated in Fig. 5.

It will be understood that a series of 45 plates 50 bolted together at their adjacent ends form the entire outer wall of the form, and a cooperating series of similar plates 50^a form the entire inner wall, as illustrated in Fig. 3. The angles 53 are so spaced on 50 the plates that they always occur in pairs on the exterior sides of the plates 50 and 50^a, in exactly opposite positions, as shown in Figs. 3 and 5.

The universal joints 9 are used at frequent 55 intervals, so that small variations in the alignment of the shafting are immaterial.

The use and operation of this apparatus is as follows:

A series of plates 50 are placed end to 60 end, with their terminal angle irons lying on the outside, and the latter are bolted together, so as to form in effect a single plate extending entirely around the space which is 65 to be filled with the concrete to form a wall

of the desired shape and dimensions. Another series of similar plates 50^a is likewise bolted together, and positioned inside the first series at the required distance, which is the thickness of the wall that is to be made. 70 The two series of plates are then connected together and the spacing is determined and made permanent by means of the braces 56 and 57 placed between each of the cooperating pairs of angle members 53. It will 75 be observed that these braces are of considerable size, so as to be entirely rigid. They are preferably made up of hollow pipe members having terminal flanges 60 at their ends. Bolts extend through the pipes and 80 are secured at their ends outside the angle iron members by nuts 61. By this construction the braces may be removed without spreading the plates or supports. The 85 nuts 61 clamp the angles rigidly to the brace, as clearly illustrated in Fig. 5. The two braces 56 and 57, when clamped in position as illustrated, determine the spacing of the plates 50, and prevent these members from spreading apart under pressure of 90 concrete that is poured therebetween.

After the inner and outer wall forms have been placed in position as illustrated in Fig. 1, conforming to the shape of the wall that is to be built, the supports 8 are 95 set up, with the shafts 5, 12, 15, 18, 24, and 21 carried thereon, and the motor is connected to this shafting through the chain 3. The hoisting chains 41 are attached by 100 loops 65 to the braces 57, as illustrated at the left of Fig. 2.

Then fluid concrete is poured into the form until it is partly filled. Preferably the concrete mixture is added continuously through a spout, which passes at a uniform speed 105 around the wall depositing a thin layer of concrete. By the time several inches of this have been uniformly laid all the way around, the bottom of it is strong enough to bear the weight of additional concrete to be 110 added, and strong enough to maintain its molded structure. Then the motor may be started, and the entire frame raised slowly and continuously, fluid concrete being constantly added in thin layers to the top of 115 the wall, at the same rate that the form is hoisted. By this means a continuous operation may be carried on, and the wall will be built much faster than with the use of forms which have to be torn down at the 120 end of each filling. Although fluid concrete is referred to throughout this specification, it is to be understood that I may use the ordinary mortar like, or semi-dry mixture, tamping it into place by hand. The principle is the same.

When the concrete wall is to be built up past cross girders, beams, window frames, or the like, an extra brace may be put into 125 the middle position shown in Fig. 5, that is, 130

through the intermediate holes through the upper extension of the angles 53. Then the upper brace 57 may be removed when it comes to the lower edge of said cross girder, 5 or frame. The chain 41 is then attached to the brace in the intermediate position, and the form is pulled up until the upper ends of the extension has passed above the girder or frame, then the brace is replaced in the upper 10 hole, the middle one removed and the form lifted until the girder comes in contact with the lower brace 56. The middle one is then replaced and the lower one removed, thus always holding the form in rigid position by two braces, until it has been pulled above the girder, when the braces may be replaced in their normal position in the upper and lower holes. By this construction I am enabled to continuously build my walls past cross girders, window frames or the like, which are necessarily positioned in the path of the form. It is not necessary with this construction to tear down the form or to make any special change in order to pass such obstructions.

Manifestly, it is not necessary to use this apparatus so as to continuously lift the forms, but they may be filled, allowed to set, and then hoisted a distance slightly less than the depth of the form, refilled, etc. Even when used in this way the apparatus has distinct advantages, but the chief value lies in its capacity for continuously forming and building a concrete wall.

35 By this continuous process, even after the form has been lifted the concrete is still fresh enough just below the form to give it a trowel finish, but stiff enough to hold its shape.

40 I claim:

1. Apparatus for molding concrete walls comprising two metal plates spaced apart the width of the wall to be made, said plates having attached to their exterior sides upright members extending above the upper edges of the plates, said extensions in that portion above the plates having three or more pairs of aligned perforations therein, and two or more removable cross members adapted to engage corresponding pairs of perforations whereby to hold the plates accurately spaced apart in vertical relation while permitting the removal of one of said cross members.

55 2. Apparatus for building concrete walls comprising two series of detachable connecting metal plates adapted to form the sides of a wall, two or more vertical angle iron members attached to the exteriors of said plates and extending above the upper edge thereof, said extensions being oppositely po-

sitioned on cooperating pairs of plates and having three or more horizontally aligned perforations therein, and a plurality of removable cross members adapted to rigidly engage the said extensions by means of the aligned perforations therein, whereby to hold the plates in accurately spaced relation, and means to raise the said plates without detaching more than one of the cross members at any one time.

3. Apparatus for molding concrete walls comprising two metal plates adapted to form the sides of a wall, oppositely placed upright members rigidly attached to the exterior sides of the said plates and extending above the upper edge thereof, three or more horizontally aligned perforations in each of said extensions above the edge of the plates, two cross members adapted to be rigidly but removably attached to said extensions by engagement with similarly positioned perforations in said extensions, and means to raise the apparatus as a whole.

4. Apparatus for molding concrete walls comprising a series of plates detachably connected to each other at their ends and forming the outer wall of a form, a series of similar plates detachably connected to each other and forming the inner wall of the form, spacing means for said plates comprising upward extensions therefrom, with connecting bars extending between said upward extensions above the upper edges of the plates, a line of driven shafting extending above the form and supported thereabove, chain and sprocket connections from said shafting to the said upward extensions, and means to rotate the shafting whereby to lift the form.

5. Apparatus for molding concrete walls comprising a series of plates detachably connected to each other at their ends and forming the outer wall of a form, a series of similar plates detachably connected to each other and forming the inner wall of the form, spacing means for said plates comprising upward extensions therefrom with three or more oppositely disposed sets of perforations in upward extensions, and three or more connecting bars being adapted to be shifted vertically to different sets of said perforations, whereby to permit the passage of obstructions in the upper path of the form, and means to lift the form as a whole.

In testimony whereof, I have hereunto set my hand.

WILLIAM S. DUNHAM.

Witness:

E. A. TURNER.
